(Cl. D44—15)

To the Commissioner of Patents:

Be it known that I, Joseph Hackley, a British subject, of Tunstall, Stoke-on-Trent, England, whose post-office address is the same, have invented a new, original, and ornamental Design for a Dinner Plate, of which the following is a specification, reference being had to the accompanying drawing, forming a part thereof.

Fig. 1 is a top view of a dinner plate, showing my new design.

Fig. 2 is an edge or side view of a dinner plate, showing my new design.

I claim:

The ornamental design for a dinner plate, as shown.

JOSEPH HACKLEY.
